(57) **CLAIM**

The ornamental design for a shade actuator rod, as shown and described.

DESCRIPTION

FIG. 1 is a perspective top front right view of a shade actuator rod, showing my new design;

FIG. 2 is a perspective top rear left view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is an enlarged top plan view; and,

FIG. 10 is an enlarged bottom plan view thereof.

1 Claim, 3 Drawing Sheets
